LADDER

Keith David Bernkrant, Miami, Fla., assignor to
Firearms Import & Export Corp.

Filed Feb. 9, 1976, Ser. No. 656,377

Term of patent 14 years

Int. Cl. D6—99

U.S. Cl. D25—64

FIG. 1

FIG. 2

FIG. 3

FIG. 4

FIG. 5

FIG. 6

FIG. 1 is a front elevational view of a ladder showing my new design;

FIG. 2 is a side elevational view thereof;

FIG. 3 is a top plan view thereof;

FIG. 4 is an enlarged fragmentary sectional view taken along line 4—4 of FIG. 1;

FIG. 5 is a front elevational view thereof in its folded condition; and

FIG. 6 is a top plan view of FIG. 5.

The characteristic feature of my design resides in the arrangement of separate coupling members adjacent the upper and lower surfaces of each step and the pattern of vertically spaced grid works formed by the vertical members at the ends of each step as best illustrated in FIG. 2.

I claim:

The ornamental design for a ladder, as shown and described.
